WILLIAM KIRKHAM, OF SPRINGFIELD, MASSACHUSETTS.

Design No. 4,554, dated January 3, 1871.

DESIGN FOR AN EGG-STEAMER.

The Schedule referred to in these Letters Patent and making part of the same.

I, WILLIAM KIRKHAM, of Springfield, Hampden county, Commonwealth of Massachusetts, have invented and produced a new and original Design for an "Egg-Steamer," of which the following is a specification.

The nature of my design is fully represented in the accompanying drawing, to which reference is made, and consists of a steamer for eggs, of the shape, and, as near as possible, the size, of an ostrich egg, sur-

mounted by an ostrich standing upon a field frosted or otherwise made to represent a plain of sand.

Claim.

I claim as my invention—
The design for an egg-steamer, as shown.
Witnesses: WILLIAM KIRKHAM.
